CLAIM

The ornamental design for a toner cartridge for a laser printer, as shown and described.

DESCRIPTION

FIG. 1 is a bottom plan view of a toner cartridge for a laser printer in accordance with the present invention;

FIG. 2 is a front elevation view thereof;

FIG. 3 is a top plan view thereof;

FIG. 4 is a rear elevation view thereof;

FIG. 5 is a right side elevation view thereof;

FIG. 6 is a left side elevation view thereof;

FIG. 7 is a top, rear, right side perspective view thereof;

FIG. 8 is a top, front, right side perspective view thereof; and,

FIG. 9 is a bottom, front, right side perspective view thereof.
